UNITED STATES PATENT OFFICE.

JOSIAH W. DYER, OF PHILADELPHIA, PA., ASSIGNOR TO THE AUTOMATIC CURRENT PROTECTOR AND ELECTRIC MANUFACTURING COMPANY.

CIRCUIT-BREAKER AND LIGHTNING-ARRESTER FOR ELECTRIC CIRCUITS.

SPECIFICATION forming part of Letters Patent No. 289,630, dated December 4, 1883.

Application filed May 7, 1883. (No model.)

To all whom it may concern:

Be it known that I, JOSIAH W. DYER, of the city of Philadelphia, county of Philadelphia, and State of Pennsylvania, have invented 5 an Improvement in Combined Circuit-Breaker and Lightning-Arrester for Electric Circuits, of which the following is a specification.

My invention has reference to combined 10 circuit-breaker and lightning-arrester for telephone and telegraph circuits; and it consists in certain construction of apparatus, the details of which are fully set forth in the following specification, and shown in the accompanying 15 drawings, which form part thereof.

The object of my invention is to provide a suitable instrument to be interposed in an electric circuit, which shall either ground the 20 excessive charge of electricity, due to lightning striking the electric wire, or, if the same be of low tension and large quantity, shall break said line-circuit to protect the telephone, telegraph-instruments, or any electrical cable to which it is applied. It is equally 25 adapted to protect the said instruments against excessive charges of electricity, due to the crossing of a dynamo-electric circuit (electric-light circuit) with the telephone or telegraph wire, and in this case, as the charge is constant, the 30 line is automatically broken and kept open. If from any cause the circuit-breaking mechanism should be injured, then the current would be grounded, provided it have sufficient tension. When the circuit or line is broken, an 35 alarm may be sounded, and so notify the operator.

In the drawings, Figure 1 is a side elevation of my combined circuit-breaker and lightning-arrester, and Fig. 2 is a plan view of two of 40 such instruments arranged upon the same stand.

A is the base. B is the electro-magnet, the core C of which is made like a horseshoe, and only one leg of which has the coil of wire 45 wound thereon. This makes the instrument more compact and increases its strength with a given amount of wire, thus reducing the resistance in the line to a minimum and increasing the strength of the magnet to a maximum. 50 The extra resistance inserted in the line by interposing the magnets of the circuit-breaker is objectionable, particularly in telephony,

and it is desirable to reduce this resistance to a minimum without reducing the strength of the magnet below that required to make the 55 circuit-breaker operate under all conditions; and to do this I use a horseshoe-core with a coil about one of its legs only, as set forth.

D is the armature, and is provided on its end with a catch, d, and is secured to the post 60 E by a spring, D', to withdraw the said armature away from the poles of the electro-magnets. The post E is connected to a plate, F, by a thumb or milled screw, G, which plate is in circuit with one end of the contact-block H of 65 the lightning-arrester, the other end of which rests upon support i, and is secured to a binding-post, I, to which the line-wire M is connected. This block H rests upon a ground-block, J, provided with a binding-post, L, for the 70 ground-wire l.

The blocks H and J may be made of metal or carbon, and are separated by a paper asbestos sheet, K; but I prefer to make the blocks of carbon and separate them by a thin 75 sheet of asbestos, because the carbon is not so apt to fuse and form points to make continuous grounds as are metal, and the asbestos, when perforated by a current of high tension, does not carbonize, like paper, and form 80 a continuous ground, so that by using asbestos between the contact-blocks the insulating layer or sheet K would not have to be changed for an indefinite period. It might be perforated in a hundred places without permanently 85 grounding the instrument. This is particularly useful in telephone and telegraph circuits, as it obviates the necessity of constantly changing this insulation, as was formerly necessary when paper was used. Asbestos has an 90 additional feature in its favor, and that is, that it is not as good a non-conductor as paper, and may be used thicker with the same effects, thus separating the blocks J and H to a greater extent, and thereby tends to prevent permanent 95 grounding. Of course it is evident that the said blocks H and J might be separated by air only; but in this case it would be necessary to put them very close to each other, and much danger would occur from dust or a small 100 grain of carbon getting between them, and would in time make a permanent ground. When a large number of these instruments are placed side by side, the ground-plate of carbon

would offer considerable resistance, owing to its length, and to reduce this I place a copper strip or plate, J', under said carbon J and connect it with the ground binding-post L.

- 5 Pivoted to a support, n', is the hooked arm N, the upper part of which is curved over and terminates in a catch, n, adapted to be caught by the part d of the armature D. When pressed up and caught, it compresses or bends 10 a spring, O, and when released by the armature D the arm N is thrown back and is caught between two spring-pieces, P, and supported there. The said arm N, in being caught by said springs, closes a local-alarm circuit, Q, 15 provided with a battery, Q', and alarm-bell or buzzer Q'. When the arms N are down and it is desired to raise them to close the circuit, if the line M be charged by a continuous current, as from an electric-light circuit, the 20 moment the parts d and n touch, the operator would receive a heavy shock. To prevent this I provide said arms N with hard-rubber buttons N', so that when the arm is pressed up and caught by the armature D it will immediately drop, and thus indicate a continuous 25 powerful current. As the arm N forms part of the line, it would be impossible to hold it without such protection against shocks. The bottom of arm N or support n' is connected with 30 one end of the helix of the electro-magnet B by wire T, the other end of which helix is connected by wire S with binding-post R, to which the other or grounded end of the line M is secured, and having located therein the receiving-instrument T.

35 I do not claim that the principle of breaking a telephone or telegraph circuit is new, nor that the broad principle of the mechanism is new, but confine myself to the peculiarities 40 of the construction of said mechanism, whereby greatly-improved results are obtained.

The operation is as follows: The line M enters at binding-post I and leaves the instrument by binding-post R, having passed through 45 block H, conductor F, post E, armature D, arm N, wire T, magnet B, and wire S. Now, should an excessive charge of lightning of high tension strike the wire M, then the said charge would pass to ground by block J and wire l; 50 but should there be considerable quantity the magnet B would attract the armature D and open the line-circuit and ring the alarm Q', or it may perform both of said functions—i. e., pass to ground and break the circuit. If the 55 electric charge be due to crossing with an electric-light wire, then the line is broken and the alarm Q' rings, and if it is attempted to close the line by raising arm N the armature is immediately attracted and the arm N drops, 60 while in the case of the line being opened by a lightning-charge the arm N is caught and retained, as the armature is not again attracted so as to free said arm N; hence the cause is at once known.

65 In this application I do not claim the specific construction of the lightning-arrester, as

that will form subject-matter of a future application.

Having now described my invention, what I claim as new, and desire to secure by Letters 70 Patent, is—

1. The combination of line-circuit M, having receiving-instruments located therein, with a lightning-arrester and a circuit-breaker, the circuit-breaker being located in the line between the lightning-arrester and receiving-instruments, substantially as and for the purpose specified. 75

2. A line-circuit and an electro-magnet located therein, in combination with a pivoted 80 arm adapted to break the line-circuit, and latching mechanism controlled by said magnet and its armature to hold said arm, means to catch said arm when freed, and means, as set forth, actuated by said pivoted arm to 85 sound an alarm after said line is broken, substantially as and for the purpose specified.

3. The combination of horseshoe-core C with a helix, B, about one of its legs, armature D, arm N, and wire T, the said armature 90 being in circuit with one end of the line-wire, and helix B with the other end, substantially as and for the purpose specified.

4. The combination of conducting-blocks H and J with insulating medium K, line M, 95 ground-wire l, an electro-magnet armature, D, having catch d, arm N, spring O, horseshoe-core C, helix B on one leg of said magnet, and means to draw said armature away from the core, the electro-magnet being in circuit 100 with the line, and located between the receiving-instruments and the conductors H and J, substantially as and for the purpose specified.

5. The combination of conducting-blocks H and J with insulating medium K, line M, 105 ground-wire l, an electro-magnet armature, D, having catch d, arm N, spring O, horseshoe-core C, helix B on one leg of said magnet, and means to draw said armature away 110 from the core, springs P, forming the terminus of an alarm-circuit, the electro-magnet being in circuit with the line, and located between the receiving-instruments and the conductors H and J, substantially as and for the purpose specified.

6. The combination of conducting-blocks H and J with insulating medium K, line M, ground-wire l, an electro-magnet armature, D, having catch d, arm N, spring O, horseshoe-core C, helix B on one leg of said magnet, means to draw said armature away from the core, springs P, circuit Q, battery Q', and alarm Q', the electro-magnet being in circuit 120 with the line, and located between the receiving-instruments and the conductors H and J, substantially as and for the purpose specified. 125

In testimony of which invention I hereunto set my hand.

JOSIAH W. DYER.
